UNITED STATES PATENT OFFICE.

AUGUST C. MORGAN, OF GROOM, TEXAS.

ENGINE-STARTER.

1,065,708.

Specification of Letters Patent. Patented June 24, 1913.

Application filed July 31, 1912. Serial No. 712,551.

To all whom it may concern:

Be it known that I, AUGUST C. MORGAN, a citizen of the United States, residing at Groom, in the county of Carson and State of Texas, have invented certain new and useful Improvements in Engine-Starters, of which the following is a specification, reference being had to the accompanying drawings.

10 This invention relates to new and useful improvements in engine starters for automobiles and more particularly to a foot starting device and my object is to provide a device which, by mere pressure of the 15 feet of the operator, on foot pedals will start the motor.

A further object of the invention resides in providing a connection for disposing the 20 crank handle shaft in engagement with the crank shaft and an independent connection for rotating said crank handle shaft and crank shaft.

25 A further object of the invention resides in providing a device which is extremely simple and durable in construction, inexpensive to manufacture and one which will be very efficient and useful in operation.

With these and other objects in view, the 30 invention consists in the novel features of construction, combination and arrangement of parts as will be hereinafter referred to and more particularly pointed out in the specification and claims.

In the accompanying drawings forming 35 a part of this application, Figure 1 is a side elevation partly in section showing my improved device applied to an automobile. Fig. 2 is a vertical longitudinal section through the operating means for the crank 40 handle shaft. Fig. 3 is a vertical transverse section as seen on line 3—3, Fig. 1, looking forwardly. Fig. 4 is a vertical transverse section as seen on line 4—4, Fig. 2. Fig. 5 is a fragmentary horizontal section as seen 45 on line 5—5, Fig. 1. Fig. 6 is a fragmentary perspective view of one of the locking dogs; and Fig. 7 is a similar view of the other locking dog.

In describing my invention, I shall refer 50 to the drawings in which similar reference characters designate corresponding parts throughout the several views and in which—

1 indicates the frame of an automobile of any desired type having the engine 2 55 properly mounted therein and extending through the front of the machine below the

radiator thereof, is the usual crank handle shaft 3 which is adapted to be engaged with the crank shaft 4 of the motor by the usual clutch mechanism 5. My improved device 60 contemplates the rotation of this crank handle shaft and crank shaft from the seat of the automobile. The crank handle is not mounted directly on the shaft 3, but is separated therefrom as shown at 6, the 65 free end of said shaft 3 being designed square in cross section, so as to readily receive the socket portion of said crank.

Fulcrumed intermediate of its ends, on a bracket 7 which is carried on the frame of 70 the vehicle, is a lever 8 which extends through a slot 9 in the foot board of the vehicle to be readily operated by the foot of the driver and the lower end of said lever has engaged therewith a flexible connection 10. The opposite end of this connection 10 is connected to an arm or lever 11 which is pivoted at its lower end to the forward end of the frame, the upper end of said lever or arm 11 being provided with 80 a yoke or the like 12 which is loosely engaged with the crank handle shaft 3 in the rear of the clutch 5 thereon. The usual spring 13 encircling the crank handle shaft 3 normally retains the clutch 5 in its ineffective position and by placing the foot on the free end of the lever 8, and pressing forwardly thereon, the lever 11 will be drawn rearwardly to correspondingly draw the crank handle shaft 3 rearwardly, whereby the clutch 5 will be effectively disposed. In order to retain the clutch 5 in its effective position, a ratchet 14 is formed in the one side of the slot 9, while the one side of the lever is beveled or similarly designed, 95 as shown at 15 to be readily received in the teeth of the ratchet. Thus when the clutch has been effectively positioned, the lever may be engaged with the ratchet teeth to retain the same in such position. Also fulcrumed 100 on the frame 1, is an additional foot lever 16 which extends through a slot in the foot board of the vehicle adjacent the lever 8 to be also readily engaged by the foot of the operator. The lower end of this lever 105 16 has a pulley 17 mounted thereon over which extends a flexible connection 18, the one end of said flexible connection being securely engaged with the frame 1 at the point 19. This connection 18 also extends over a 110 pulley 20 at the forward end of the frame 1 and continues upwardly to be extended over

and engaged with a grooved wheel 21, which is loosely mounted on the crank handle shaft 3. This wheel has one face thereof cut away as shown at 22 and substantially telescoped within this cut away portion thereof and fitting snugly therewithin, is an additional wheel 23 which is also loosely mounted on the shaft 3. The wheel 23 is held in position with respect to the wheel 21 by means of the lugs or the like 24 which are secured to the one face of the wheel 23 and overhang a flange 25 formed on the wheel 23. This wheel 23 which is formed similar to the wheel 21, in having a cut away portion thereon, is provided with the internally arranged ratchet teeth 26, the one face of each tooth being beveled. Pivots mounted intermediate of its ends, on the inner face of the wheel 21, is a pawl 27, the one end of which is provided with a tooth 28 adapted to coöperate with the teeth 26 and a leaf spring 29 mounted on the inner face of said wheel 21 engages the pawl 27 to the one side of its pivot point to normally retain said tooth 28 in effective engagement with the teeth 26. The opposite end of the pawl 27 is adapted to engage the teeth of an additional ratchet or the like 30 which is keyed to the shaft 3 and from this construction it will be seen that as the wheel 21 is caused to rotate in one direction, said shaft 3 will also be caused to rotate.

Engaged with the wheel 21 is one end of a flat faced coil spring 31, the opposite end of said spring being engaged with the flexible connection 18, whereby it will be appreciated that when said connection has been once turned to rotate the wheel, said wheel will be again returned to its initial position, thereby winding the connection 18 thereon. This spring 31, will, therefore, take up the slack in the connection 18, after the same has once been drawn and a coil spring 32, engaged at its one end with the lower end of the lever 16 and at its opposite end to the frame 1, will dispose said lever to its initial position after having been once operated.

From the construction shown and described, it will be appreciated that after the lever 8 has once been pressed forward to effectively engage the clutch 5, it will only be necessary to force the lever 16 forwardly, which action will rotate the wheel 21 and cause the shafts 3 and 4 to be rotated in view of the ratchets 26 and 30 and the pawl 27. When the motor has once been started, the shaft 3 will be disengaged with the shaft 4 in the usual manner and should it be found, for any reason whatsoever, that the device will not operate, it will be appreciated that the same may be operated by means of the crank 6 in the ordinary manner. As often happens, upon the cranking of the motor, the engine will "back-fire" and to compensate for this action, the outer

face of the wheel 23 is provided with ratchet teeth 33 which are adapted to be engaged by the dogs 34 carried on the frame 1, when it is attempted to rotate said wheel 22 counter-clockwise. It is apparent that upon the "back-firing" of the motor, the shaft with the ratchet 30 thereon will have a tendency to rotate counter-clockwise, which will tend to force the pawl 27 and the wheel 21 therewith. The teeth 33 being engaged with the dogs 34, will prevent the movement of the wheels 21 and 23, and a slight movement of pawl 27 over the teeth 26 of said wheel 23, will throw the pawl 27 on its pivot, and thereby allow the ratchet 30 on the shaft 3 to be rotated freely and independently of the other parts of the device.

From the foregoing description of the construction of my improved device, the operation thereof will be readily understood and it will be seen that I have provided an improved engine starter for automobiles which may be readily operated by the driver from the seat of the vehicle. It will further be seen that I have provided a device which is extremely simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the invention.

Having thus described this invention, what I claim is:

1. In an engine starter, the combination with a shaft; of a wheel loosely mounted thereon, a ratchet wheel carried on said shaft and adapted to rotate therewith, an additional ratchet wheel also loosely mounted on said shaft and provided with internally arranged teeth, a pivoted pawl carried on said wheel and adapted to normally engage the teeth of said ratchet wheels, and means to rotate the first mentioned wheel, whereby said shaft will also be rotated.

2. In an engine starter, the combination with a shaft; of a wheel loosely mounted thereon, said wheel being provided with a cavity on the one face thereof, a ratchet wheel carried on said shaft and disposed within the cavity of said wheel, an additional ratchet wheel loosely mounted on the shaft and also disposed within the cavity of said first mentioned wheel, said latter ratchet wheel being provided with internally arranged teeth directed similar to the teeth of the other ratchet wheel, a pivoted pawl carried on the one face of the first mentioned wheel, the ends thereof being normally adapted to respectively engage the teeth of said ratchet

wheels, and means to rotate said first mentioned wheel.

3. In an engine starter, the combination with a shaft; of a wheel loosely mounted thereon, a ratchet wheel carried on said shaft and adapted to rotate therewith, an additional ratchet wheel loosely mounted on said shaft and provided with internally arranged teeth, means carried on said first mentioned wheel and adapted for normal engagement with the teeth of said ratchet wheels, means to rotate said first mentioned wheel clockwise to correspondingly rotate said shaft therewith, and additional means 15 to prevent the rotation of said additional ratchet wheel counter-clockwise.

4. In an engine starter, the combination with a frame and a shaft rotatably mounted thereon; of a wheel loosely mounted on said shaft, a ratchet wheel carried on the shaft and adapted for rotation therewith, an additional ratchet wheel loosely mounted on said shaft and provided with internally arranged teeth, means carried on said first mentioned 25 wheel adapted to coöperate with the teeth of said ratchet wheels, to rotate the latter upon the rotation of the former, means to rotate said first mentioned wheel, laterally extending ratchet teeth carried on the outer face 30 of said additional ratchet wheel, and a pair of dogs carried on said frame and adapted for engagement with said laterally extending teeth to prevent the counter-clockwise movement of said additional ratchet wheel 35 when the shaft is rotated counter-clockwise.

5. In an engine starter, the combination with a shaft; of a drum loosely mounted thereon, a ratchet wheel carried on the shaft and disposed within said drum, a revoluble 40 member loosely disposed in said drum, means carried on said drum coöoperating with said ratchet wheel and said loosely mounted member to rotate said shaft upon the rotation of said drum in one direction,

means to rotate said drum in one direction, 45 and additional means to prevent the rotation of said revoluble member therein in the opposite direction.

6. In an engine starter, the combination with a frame, and a shaft rotatably mounted thereon; of a drum loosely mounted on said shaft, a ratchet wheel carried on the shaft within said drum, an additional ratchet wheel loosely and revolubly mounted within said drum, means carried on the drum 55 adapted to coöperate with the teeth of said ratchet wheels to rotate the latter upon the rotation of the former, laterally extending ratchet teeth formed on the peripheral edge of the additional ratchet wheel, and a pair 60 of yielding dogs carried on said frame on opposite sides of said shaft and adapted for engagement with said last mentioned teeth to prevent the counter-clockwise movement of said additional ratchet wheel. 65

7. In an engine starter, the combination with a shaft; of a drum loosely mounted thereon, a ratchet wheel carried on said shaft and disposed within said drum, an additional ratchet wheel loosely and revolubly 70 disposed in said drum, said additional ratchet wheel being provided with a peripheral flange, means on said drum coöperating with the flange for retaining the additional ratchet wheel in position in the 75 drum, means carried by said drum coöperating with said ratchet wheels for rotating the shaft upon the rotation of said drum in one direction, and means coöperating with said additional ratchet wheel to prevent the 80 rotation of the same in the opposite direction.

In testimony whereof I hereunto affix my signature in the presence of two witnesses.

AUGUST C. MORGAN.
